UNITED STATES PATENT OFFICE.

HEICHI SAWAMURA, OF NEW YORK, N. Y.

FOUNTAIN-PEN.

1,178,414.

Specification of Letters Patent. Patented Apr. 4, 1916.

Application filed September 3, 1915. Serial No. 48,820.

To all whom it may concern:

Be it known that I, HEICHI SAWAMURA, a subject of the Emperor of Japan, residing at New York city, in the county of New York and State of New York, have invented new and useful Improvements in Fountain-Pens, of which the following is a specification.

This invention relates to fountain pens and it consists in the novel features herein-after described and claimed.

An object of the invention is to provide a fountain pen of simple structure having its parts so arranged that the ink may be readily fed to the pen point.

Another object of the invention is to provide means for readily filling the bulb or sack which contains the ink.

With these objects in view the pen comprises a barrel or handle having a slot disposed longitudinally thereof. A plug is inserted in one end of the barrel or handle and is provided with a feed bar which has contact at one end with the pen point. The pen point is held in position in the barrel or handle by the said plug, and the plug and bar are provided with a longitudinally disposed opening. A flexible sack is connected with the said plug and a spring is mounted upon the plug and extends along the sack. A block is slidably mounted in the barrel or handle and is adapted to move along the said spring whereby the said spring is flexed and the side of the sack is moved in an inward direction whereby the sack expels the ink through the opening in the plug and feed bar.

In the accompanying drawing:—Figure 1 is a plan view of the pen. Fig. 2 is an enlarged side elevation of the same with parts in section. Fig. 3 is a plan view of the feed bar and plug. Fig. 4 is a side elevation of the sack detached from the plug.

As illustrated in the accompanying drawing, the pen comprises a barrel or handle 1 which is provided in the vicinity of one end with a longitudinally disposed slot 2. A plug 3 is fitted in one end of the barrel or handle 1 and is provided at its periphery with a recess 4 adapted to receive the end portion of a pen point 5 whereby the said point is frictionally held in the handle between the inner side thereof and the exterior of the plug 3. The plug 3 is provided with a feed bar 6 the lower end of which is curved as best shown in Fig. 2 of the drawing. The

plug 3 and the feed bar 6 are provided with a longitudinally disposed opening 7, one end of which terminates adjacent the inner surface of the pen point 5. A flexible sack 8 is attached to the inner end of the plug 3 and surrounds the inner end of the opening 7 as best shown in Fig. 2 of the drawing. A spring 9 is attached to the plug 3 and extends longitudinally along the sack 8. A block 10 bears at its inner side against the outer surface of the spring 9 and the said block is provided with a shank 11 which passes through the slot 2 and which in turn is provided at its outer end with an enlarged head 12.

When the sack 8 is supplied with a suitable quantity of ink and it is desired to cause the same to flow from the said sack through the opening 7 to the pen point 5, the block 10 may be moved along the spring 9 whereby the said spring is flexed in an inward direction and the side of the sack 8 is compressed and thus the ink is forced from the said sack through the opening 7 to the pen point 5. From the point where the ink arrives upon the pen point 5 it may gravitate or move by capillary action to the ends of the nibs of the point. During the movement of the block 10 along the spring 9, the slot 2 acting in conjunction with the shank 11 serves as a guide for the block and holds the same in position against the side of the spring 9.

From the foregoing description taken in conjunction with the accompanying drawing, it will be seen that a fountain pen of simple structure is provided and that the parts thereof may be easily and quickly manipulated to cause the ink to flow from the sack to the point of the pen. When it is desired to refill the sack 8 with ink, the plug 3 is detached from the handle 1 and the said sack is compressed between the fingers whereby the air is forced from the sack. The lower end of the feed bar 6 is then immersed in the ink and pressure from the sides of the sack 8 is removed whereby the sack expands and a partial vacuum is created therein which causes the ink to flow up through the opening 7 and partially or completely fill the said sack.

Having described the invention what is claimed is:—

A fountain pen comprising a handle having a longitudinally disposed slot, a plug inserted in the handle and having a feed

bar, said feed bar and plug having an opening, a sack mounted on the plug and surrounding one end of the opening, a flexible spring mounted upon the plug and extending along the sack under the slot, the end portions of the spring projecting beyond the ends of the slot, and a block having a shank located in the slot, the slot serving as means for guiding the block along the

spring to flex the same and compress the 10 sack when the shank is moved in the slot.

In testimony whereof I affix my signature in presence of two witnesses.

HEICHI SAWAMURA.
